WALL PANEL

Philip Carver, Bayside, N. Y.

Application November 24, 1954, Serial No. 33,234

Term of patent 7 years

(Cl. D13—1)

FIG. 1.

FIG. 2

Fig. 1 is an elevational view of a wall panel showing my new design; and

Fig. 2 is a cross sectional view taken on line 2—2 of Fig. 1.

I claim:

The ornamental design for a wall panel, substantially as shown.
